CLAIM

The ornamental design for a water generator housing as shown and described.

DESCRIPTION

FIG. 1 is a top front perspective view of a water generator housing showing our new design.

FIG. 2 is a bottom rear perspective view of the water generator housing of FIG. 1.

FIG. 3 is a front view the water generator housing of FIG. 1.

FIG. 4 is a back view of the water generator housing of FIG. 1.

FIG. 5 is a left side view of the water generator housing of FIG. 1.

FIG. 6 is a right side view of the water generator housing of FIG. 1.

FIG. 7 is a top view of the water generator housing of FIG. 1; and,

FIG. 8 is a bottom view of the water generator housing of FIG. 1.

The broken lines are directed to unclaimed features of the water generator housing and form no part of the claimed design.
